UNITED STATES PATENT OFFICE.

ALBERT A. GORDON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

WEFT-DETECTING MECHANISM FOR DROP-BOX LOOMS.

Application filed January 26, 1926. Serial No. 83,859.

This invention relates to weft detecting mechanism for use in connection with a plurality of shifting shuttle boxes in a drop box loom.

5 It is the general object of my invention to provide a separate detector for each shuttle box combined with a selective indicating device by which the particular detector is rendered operative which corresponds to the 10 shuttle which is about to become active.

A further object of my invention is to provide improved mechanism by which an indication of weft exhaustion by any one of the detectors will be transmitted to the weft 15 replenishing mechanism.

My invention further relates to certain arrangements and combinations of parts which will be hereinafter described and more particularly pointed out in the appended 20 claims.

A preferred form of my invention is shown in the drawings in which—

Fig. 1 is the front elevation of a portion of the drop box end of a loom embodying 25 my improvements;

Fig. 2 is the plan of the parts shown in Fig. 1;

Fig. 3 is an enlarged detail sectional plan view, taken along the line 3—3 in Fig. 1;

30 Fig. 4 is a detail sectional elevation, taken along the line 4—4 in Fig. 3;

Fig. 5 is a detail sectional elevation, taken along the line 5—5 in Fig. 2;

Fig. 6 is a detail sectional elevation of 35 certain parts, taken along the line 6—6 in Fig. 1;

Fig. 7 is a plan view of the parts shown in Fig. 6;

Fig. 8 is a view similar to Fig. 7 but 40 showing the parts in a different position;

Fig. 9 is a detail sectional plan view, taken along the line 9—9 in Fig. 4;

Fig. 10 is a perspective view of one of the supports for the detectors; and

45 Fig. 11 is a diagrammatic side elevation of the mechanism provided for selectively rendering the detectors operative.

Referring to the drawings, I have shown 50 portions of a loom frame 20, a breast beam 21 and a lay 22 having the usual drop box lay end 23. A series of drop boxes 24 are movable vertically in the lay end 23 and are positioned by a lifter rod 25, actuated by any suitable form of drop box mechanism,

not shown. The drop boxes 24 are provided 55 with front box plates 26 and binders 27, both provided with slots or openings 28 through which a weft detector 29 may enter the shuttle and engage the weft carrier therein.

The weft detector 29 is shown as being of 60 the usual "side-slip" type and in itself forms no part of my present invention. Each detector 29 is slidably mounted upon a plate 30, secured to an arm 31 (Fig. 10) forming a part of a detector stand 32. A spring 65 33 for each detector 29 forces the detector yieldingly inward to engage the weft carrier in the forwardly moving shuttle. When thus engaged by a weft carrier having a sufficient supply of weft thereon, the detector 70 is moved directly forward without slipping sideways, but if engaged by a substantially exhausted weft carrier the detector slips to the right, as viewed in Fig. 2, and engages the upright portion of a transmitting member 35 (Fig. 6) pivoted at 37 and 38 to the upper and lower portions of the drop box frame 24.

75 A rod or plunger 40 (Figs. 7 and 8) is pivoted at 41 to the member 35 and the opposite end of the rod is normally positioned as indicated in Fig. 7, just clearing a depending projection 42 (Fig. 1) formed on the end of an arm 43 pivoted at 44 (Fig. 2) on a bracket 45, mounted on the breast beam 80 21.

85 The right hand end 46 of the arm 43 extends under a blade or dagger 47 pivoted at 48 (Fig. 5) to an arm 49 secured to a rod or shaft 50. The shaft 50 (Fig. 2) is mounted in bearings below the breast beam 21 and extends across the loom to the weft replenishing mechanism, with which it cooperates through certain connections which are of the usual type and form no part of my present 90 invention.

95 The end 46 (Fig. 5) of the arm 43 is normally seated in a recess 52 in the blade 47, and the blade then occupies the lower position indicated in full lines in Fig. 5. If, however, the rod 40 engages the depending projection 42 of the arm 43 as the lay moves forward, the end 46 of the arm 43 will be moved rearward out of the recess 52, thus raising the blade 47 to the dotted line position indicated in Fig. 5. When thus in raised position it will be engaged by the usual cam follower or snake head 54 (Fig. 105

2) and will be forced forward, rocking the shaft 50 and indicating a transfer to the magazine or weft replenishing mechanism.

A spring 55 (Fig. 7) normally swings the 5 member 35 against a fixed abutment 56 and thus holds the rod 40 yieldingly in withdrawn or inoperative position.

I will now describe the mechanism for selecting a given detector and for rendering 10 the same operative. For this purpose, I provide each detector stand 32 with a vertical extending plate 60 (Fig. 10) these plates being located at different distances from the axis of a fixed stud 61 (Fig. 4), 15 upon which the stands 32 are pivotally mounted. The plates 60 are thus supported in parallel relation and are conveniently positioned for selective engagement by an upright arm of a member 64 secured to a rod 65 20 (Fig. 3) which is slidable in bearings 66 in a bracket 67 secured to the lay end 23 and movable forwardly and rearwardly therewith.

A rearwardly projecting portion 68 of the 25 member 64 is connected to a cable, chain or other flexible element 69 which extends downward to a guide pulley 70 (Fig. 11) positioned substantially at the axis of oscillation of the lay. The flexible element then 30 extends upward and rearward to a point of connection with a positioning lever 71 (Fig. 11).

The lever 71 is mounted upon a fixed pivot 72 and the rear end of the lever 71 is pivotally connected at 73 to a short floating lever 74. The lever 74 is connected by a link 75 to a dobby lever 76 mounted upon a fixed pivot 77 and connected in turn by a link 78 to a pattern lever 79. The opposite end of 40 the floating lever 74 is similarly connected by a link 80 to a second dobby lever 81 which is connected to a second pattern lever 79.

The pattern levers are controlled by blanks 45 or risers on a pattern chain 82 and the dobby levers 76 and 81 are connected by links 83 to control the usual drop box actuating mechanism. By various combinations of blanks and risers acting through the pattern levers 50 79, the positioning lever 71 may be moved to different desired position, corresponding to the ensuing movements of the drop boxes. By its connection through the cord or chain 69, such movement of the lever 71 positions 55 the arm 64 (Fig. 4) opposite the plate 60 corresponding to the detector for the shuttle about to be moved to active or running position by the drop box mechanism.

It will be noted that this selective movement is taken direct from the pattern chain and thus occurs substantially in advance of the movement of the drop boxes and in the early part of the forward movement of the lay. As the lay thereafter moves forward, 60 a cam roll 85 (Fig. 3) on the end of the slid-

ing rod 65 engages a fixed cam bar 86 mounted on a bracket 87 (Fig. 2) formed on the loom side 20.

Such an engagement of the roll 85 with the cam bar 86 slides the rod 65 to the left, 70 as indicated in Figs. 2 and 3, moving the selective arm 64 bodily to the left and swinging the particular stand 32 engaged by said arm to the operative position indicated in Fig. 2. This swinging movement takes place 75 about the axis of the stud 61 (Fig. 4) which is fixed on plates 88 secured to the drop box frame 24 (Fig. 1).

Each stand 32 is provided with a segmental slot 90 (Figs. 9 and 10) in which is 80 inserted a fixed stop pin 91. A coil spring 92 is fixed at one end in the stud 61 and the other end of the spring engages the corresponding stand 32 and acts to yieldingly swing the stand to a forward or inoperative 85 position.

A spring 93 (Fig. 3) is mounted upon the sliding rod 65 between one of the bearings 66 and the rearwardly extending arm 68 and acts to yieldingly raise said arm, putting 90 tension on the flexible connection to the positioning lever 71. The spring 93 also moves the rod 65 yieldingly to the right.

Having thus described my invention, the method of operation thereof will be readily 95 apparent. As the lay begins its forward movement, the selective arm 64 is moved by the pattern mechanism to a position facing a selected plate 60. As the lay continues its forward movement, the cam roll 85 is engaged by the cam bar 86 and the arm 64 is thereby moved sideways, swinging the selected weft detector stand on the stud 61 and causing the corresponding detector 29 to engage the weft carrier in the shuttle 100 about to become active.

If the weft carrier is substantially exhausted, the detector slips sideways, engaging the bar 35 and pushing the rod 40 into the path of the depending projection 42 on the arm 43. As the rod thereafter moves forward with the lay, the arm 43 is swung upon its pivot, raising the blade 47 into the path of the cam follower 54 which thereupon rocks the shaft 50 and causes weft replenishment. 115

I have thus provided simple and effective mechanism by which a weft detector corresponding to a shuttle about to become active may be placed in operative position and may thereafter effectively indicate weft exhaustion. 120

Having thus described my invention and the advantages thereof, I do not wish to be limited to the details herein described, but what I do claim is:

1. In a loom having a plurality of drop boxes at one end thereof, in combination, a plurality of weft detectors corresponding in number with said boxes and associated there-

with, a single actuating means effective to render any one of said detectors operative, a pattern controlled selective connector, and means to give said connector a preliminary 5 selective movement to interpose said connector between said actuating means and a selected detector before the operating movement of said actuating means.

2. In a loom having a plurality of drop 10 boxes at one end thereof, in combination, a plurality of weft detectors corresponding in number with said boxes and associated therewith, a single actuating means effective to render any one of said detectors operative, a 15 selective device effective to form a connection between said actuating means and a selected detector, and means to move said device to form such connection in advance of the corresponding movement of said drop boxes.

20 3. In a loom having a plurality of drop boxes at one end thereof, in combination, a plurality of weft detectors corresponding in number with said boxes and associated therewith, actuating means effective to render any 25 one of said detectors operative, a selective device effective to form a connection between said actuating means and a selected detector, and pattern controlled means effective to position said selective device to operate with the detector corresponding to 30 the shuttle about to be picked from said drop boxes.

4. The combination in a loom as set forth 35 in claim 3, in which said pattern controlled means is operatively positioned in advance of the operation of said actuating means.

5. The combination in a loom as set forth

in claim 3, in which said detectors are separately movable to and from operative positions, and in which each detector has a contact plate associated therewith, and in which said selective device has a portion adapted to engage a selected contact plate and to form an operative connection between said actuating means and said plate for moving said 45 detector to operative position.

6. In a loom, a lay having a plurality of drop boxes at one end thereof, a plurality of weft detectors mounted on said boxes and corresponding in number to the number of 50 said boxes, each detector being pivotally movable about an axis on said drop boxes to and from operative position, an actuating rod for moving said detectors, a fixed cam bar to slide said rod longitudinally of the 55 lay, and a member mounted on said rod and selectively engaging said pivotally mounted detectors.

7. In a loom, a lay having a plurality of drop boxes at one end thereof, a plurality of weft detectors mounted on said boxes and corresponding in number to the number of 60 said boxes, each detector being movable to and from operative position relative to its drop box, and being movable vertically therewith, as the boxes are shifted, actuating means for said detectors and pattern controlled means effective to establish an operative connection between said actuating means 65 and a selected detector prior to the movement of the selected shuttle to moving position.

In testimony whereof I have hereunto affixed my signature.

ALBERT A. GORDON.
